(57) CLAIM

The ornamental design for a hair salon cart, as shown and described.

DESCRIPTION

FIG. 1 is a top plan view of a hair salon cart showing my new design;

FIG. 2 is a front elevational view thereof;

FIG. 3 is a rear elevational view thereof;

FIG. 4 is a top perspective view thereof; and,

FIG. 5 is a side elevational view thereof, the opposite side view being a mirror image of that shown.

The bottom plan view is not illustrated in the drawing disclosure and forms no part of the claimed design.
